CLAIM

The ornamental design for a drop cable connector, as shown and described.

DESCRIPTION

FIG. 1 is a bottom view of a drop cable connector showing our new design;

FIG. 2 is a top plan view thereof;

FIG. 3 is a first side elevation view thereof;

FIG. 4 is a second side elevation view thereof;

FIG. 5 is a rear elevation view thereof;

FIG. 6 is a front elevation view thereof; and,

FIG. 7 is a front, top and side perspective view thereof.
